CLAMPING DEVICE

George S. Morlan, Redondo Beach, Calif., assignor of one-third to Walter A. Hite and one-third to W. Earl Hirtensteiner, both of Redondo Beach, Calif.

Application December 8, 1945, Serial No. 633,700

7 Claims. (Cl. 248—305)

1

My invention relates to clamping devices particularly adapted to hold articles such as clothes, dish towels, dusters, and the like in a secure but readily releasable condition.

An object of the invention is to provide clamping means of the kind described which may be made up in a variety of forms to suit different arrangements, for instance, for arrangement either as individual units or in fixtures comprising a number of units for mounting on the back of a closet door and the like.

A further object of the invention is to provide a clamping device of the kind described of simple and inexpensive construction which, however, will be efficient for its purpose.

Still further objects and features of the invention will hereinafter appear from the following specification taken in conjunction with the accompanying drawings in which I have shown preferred embodiments of my invention by way of illustration, but it is to be understood that the scope of the invention is not in any way limited by this illustrative showing but only as indicated by the scope of the appended claims.

In the drawings,

Fig. 1 is a side elevation of the clamp in a form intended to be individually mounted.

Fig. 2 is a rear elevation of the clamp shown in Fig. 1 partly broken away on the line 2—2 of that figure.

Fig. 3 is a section on the line 3—3 of Fig. 2 with parts broken away.

Fig. 4 is a front elevation of the clamp shown in Fig. 1, and

Fig. 5 is a side elevation of a modified form of clamp intended to be mounted on a common support with a plurality of clamps to form a fixture which may be affixed to the back of a closet door.

In Fig. 1, the numeral 10 indicates an upper clamp arm pivoted by a pin 11 to base or support members 12 arranged one at each side of the arm. The pivoted arm 10 is provided with a hooked outer end 13 providing an inwardly facing gripping surface 14. A lower arm 16 is pivoted by a pin 17 to member 12 at a point spaced from the pivotal point of arm 10. The arm 16 is of such a length that its end 18 butts against the surface 14 of the arm 10. The surfaces 14 and 18 are preferably provided with mating corrugations.

While gravity may be utilized to keep the surfaces 14 and 18 in contact, I prefer to provide a positive engagement of these surfaces by providing a spring 19 tending to urge clamping arm 10 downwardly. The spring may consist of a

wire coiled around the pivot 11 of the upper arm and bearing at one end against the arm and at the other end against one base or support 12, though obviously any suitable type of spring may be used.

I also prefer to provide means for preventing arm 16 from falling away from arm 10 when the clamping surfaces of the arms are moved out of engagement and maintain the upper surface of the outer end of arm 16 in sliding engagement with or closely adjacent to the lower surface of arm 10 by means of a pin 20 working in a bore 22 in the outer end of the arm 10. By this construction, it will be noted that the surfaces 14 and 18 are normally in contact but that if arm 10 is rotated in the direction of the arrow shown in Fig. 3, the surfaces 14 and 18 will move apart from one another in which condition the edge of an article such as a dish towel may be inserted between these surfaces and the arm 10 released, whereupon the face 14 of arm 10 will move against face 18 of arm 16 and will firmly hold the article since any downward pull thereon will cause still firmer gripping thereof between the surfaces.

In the form of the clamp shown in Fig. 5, I have provided a spring 24 acting to urge the lower arm 28 upwardly against the under surface of the upper arm 26 and omit the pin and bore previously described with reference to Figs. 1 to 4. A spring 19 urging the upper arm downwardly is of greater strength than the spring 24 in order to insure a secure gripping action between the surface 25 on the inner edge of the rounded end of the upper arm 26 and the outer end 27 of the lower arm 28.

In order to release the grip of either form of the clamp on the article supported, it is only necessary to move the upper arms 10 or 26 upwardly, which may be readily done by pulling upwardly on the suspended article.

It will be noted that in Fig. 3 the clamp is indicated as secured to a panel 30 by means of screws 32 passing through bores in the base or support members 12. I have shown the support member 34 in Fig. 5 in the form of an angular bracket. A plurality of clamps may be mounted by screws passing through the bracket on a strip of wood or other suitable material which is in turn secured to the back of a closet door or other suitable surface. The advantage of this arrangement is that an article such as a skirt may be readily suspended from a pair of such clamping members by the waist band, or a pair of trousers may be suspended by engaging the lower ends of the trouser legs in a pair of the clamps.

In order to afford an additional means of suspending articles such as hats on the clamps, I prefer to make the lower clamping arms 14 or 28 of such a length that the upper arms 10 or 26 are maintained in an upwardly sloping direction thus serving as pegs on which the hats may be placed.

Although preferred forms of the invention have been particularly shown and described, it is contemplated that various changes and modifications can be made without departing from the scope of the invention, and it is intended to cover such changes and modifications as come within the scope of the appended claims.

I claim:

1. A clamping device comprising: a base, a top arm pivotally connected at its inner end to the base to swing relative thereto, said top arm having at its outer end a laterally projecting jaw member, a bottom arm pivotally connected at its inner end to the base to swing relative thereto and having at its outer end a jaw member disposed in opposed relationship to the first mentioned jaw member, whereby upon downward swinging movement of the arms relative to the base the jaw members will be caused to move towards each other to grip an object therebetween; and slideable means associated with the arms for guiding the jaw members in their movement.

2. A clamping device including: a vertically arranged mounting member; a first clamping arm pivoted to said mounting member and provided with a downwardly hooked end; a second clamping arm pivoted to the mounting member at a point spaced from and below the first clamping arm, said second clamping arm being of a length such that the end thereof will jam against the hooked end of the first clamping arm when the arms are rotated in downward direction; and a sliding connection holding the end of the second clamping arm from falling away from the first clamping arm whereby the end of said second clamping arm is separated from the hooked end of the first clamping arm when the arms are rotated in upward direction.

3. A clamping device including: a mounting member; a first clamping arm pivoted to said mounting member and provided with a hooked end; a second clamping arm pivoted to the mounting member at a point spaced from the first clamping arm, said second clamping arm being of a length such that the end thereof will jam against the hooked end of the first clamping arm when the arms are rotated in one direction but will separate from said hooked end when the first clamping arm is rotated in the opposite direction; and resilient means tending to rotate the clamping arms toward one another.

4. A clamping device including: a vertically arranged mounting member; a first clamping arm pivoted to said mounting member and provided with a downwardly hooked end; a second clamping arm pivoted to the mounting member at a point spaced from and below the first clamping arm, said second clamping arm being of a length such that the end thereof will jam against the hooked end of the first clamping arm when the arms are rotated in downward direction; a serrated holding surface on the contacting faces of the hooked end of the first clamping arm and the end of the second clamping arm; and a sliding

connection holding the end of the second clamping arm from falling away from the first clamping arm whereby the end of said second clamping arm is separated from the hooked end of the first clamping arm when the arms are rotated in upward direction.

5. A clamping device including: a mounting member; a first clamping arm pivoted to said mounting member and provided with a hooked end; a second clamping arm pivoted to the mounting member at a point spaced from the first clamping arm, said clamping arms being constrained for swinging movement in a common plane, and said second clamping arm being of a length such that the end thereof will jam against the hooked end of the first clamping arm when the arms are rotated in one direction; a serrated holding surface on the contacting faces of the hooked end of the first clamping arm and the end of the second clamping arm; and a sliding

20 connection holding the end of the second clamping arm from swinging away from the first clamping arm whereby the end of said second clamping arm is separated from the hooked end of the first clamping arm when the arms are swung in the opposite direction; and resilient means tending to rotate the end of the first clamping arm toward the second clamping arm.

6. A clamping device including: a vertically arranged mounting member; a first clamping arm pivoted to said mounting member and provided with downwardly hooked end; a second clamping arm pivoted to the mounting member at a point spaced from and below the first clamping arm, said second clamping arm being of a length such that the end thereof will engage against the hooked end of the first clamping arm and maintain it in an upwardly sloping direction and will jam against said hooked end when the arms are rotated in one direction but will separate from said hooked end when the first clamping arm is rotated in the opposite direction; and resilient means tending to rotate the clamping arms toward one another.

45 7. A clamping device comprising: a base including a pair of spaced support members adapted to be mounted vertically, an upper arm pivotally mounted on said base and extending outwardly therefrom, said upper arm being formed to provide an inwardly facing gripping surface extending laterally of the arm on the under side thereof, a lower arm pivotally mounted on said base below said upper arm and extending outwardly therefrom for swinging movement in the same plane as said upper arm and presenting a gripping surface at its outer end for engagement with the gripping surface of said upper arm; and means for causing said lower arm to follow said upper arm upon upward movement of said upper arm.
